**COMBINED SPATULA, CLEAVER, TURNING FORK
AND CONTAINER OPENER**

Samuel L. Gerson, Wilmington, Del.

Application October 1, 1958, Serial No. 52,842

Term of patent 7 years

(Cl. D44—29)

Fig. 1 is a top perspective view of a combined spatula, cleaver, turning fork and container opener showing my new design;

Fig. 2 is a rear elevational view thereof; and
Fig. 3 is a top plan view thereof.

I claim:

The ornamental design for a combined spatula, cleaver, turning fork and container opener, substantially as shown.
